UNITED STATES PATENT OFFICE.

CLINTON H. BECKWITH, OF CHICAGO, ILLINOIS, ASSIGNOR TO CRANE CO., OF CHICAGO, ILLINOIS, A CORPORATION OF ILLINOIS.

METHOD OF AND MEANS FOR OPERATING VALVES.

Application filed September 10, 1923. Serial No. 661,747.

To all whom it may concern:

Be it known that I, CLINTON H. BECKWITH, a citizen of the United States, residing at Chicago, in the county of Cook and State of Illinois, have invented certain new and useful Improvements in Methods of and Means for Operating Valves, of which the following is a specification.

This invention pertains generally to valve operating mechanisms, and while the principles of my invention may be utilized for various purposes, the invention is herein shown, merely for illustrative purposes, as employed in connection with a motor operated gate valve.

It has heretofore been the common practice, so far as I am aware, to operate valves of this character by a motor, in the power circuit of which was interposed a throw-out switch intended to be automatically opened so as to shut off the power supply to the motor at the exact instant that the valve reached its seat. These constructions, however, have not been satisfactory in practical operation for the reason that the valve does not close against its seat successively in the same position. The result has been, therefore, that if the switch was thrown out so that the closing movement of the valve stopped before the valve was fully seated, leakage past the valve inevitably occurred, particularly under high pressure duty. On the other hand, if, as the result of a slight accumulation of sediment or other foreign matter on the valve or the seat, the valve should jam before it reached the limit of movement for which the switch was set, in that event the motor would stall, the throw-out switch would fail to operate at all, and unless the difficulty were immediately discovered, the motor windings would be burned out.

One of the primary purposes of my present invention is to obviate the difficulties and uncertainties of operation, above mentioned, by providing a method and means for operating the valve, which will not only insure that the valve is fully seated at each closing operation, but will also insure against injury to the motor windings, and to other members of the valve operating mechanism, which would result if the current were left on the motor for any considerable length of time after the same had become stalled.

Another object of the invention is to overcome the danger of damaging the valve seats, due to the inertia of the moving parts added to the torque of the motor at the end of the travel.

With these ends in view, my invention is designed to utilize the full speed and torque of the motor for moving the valve throughout the major portion of its travel and up to a predetermined point in the travel, slightly before the actual seating occurs. At this point the torque and speed of the motor are automatically reduced so that the valve will be positively forced against its seat, but under reduced power, which is not great enough to cause injury to the valve, its seat, or the operating mechanism when movement of the valve is finally stopped, by intimate and leak tight engagement between the valve and seat. When this point is reached and further movement of the valve becomes impossible, the motor is stalled, but by reason of the reduction in current applied thereto, no injury to the motor or valve seats results. After the valve has been fully seated and the motor has been stalled, as explained, the supply of current to the motor is automatically cut off by a time relay, which was thrown into operation at the time the current to the motor was reduced, and is designed to automatically shut off the current to the motor at the expiration of a predetermined period of time after the relay goes into operation.

In addition to this method of closing the valve, which insures a positive and leak tight closing at each actuation, and also precludes injury both to the motor and the operating mechanisms, as well as to the valve and its seat, my invention contemplates an improved method and means of positively breaking or jerking the valve away from its seat, for opening purposes, without imposing excessive strains either upon the motor or the other parts of the operating mechanism.

Another feature of my invention resides in the adjustability of the operating means, which enables the reduction of current to the motor to be effected at the most desirable point in the travel of the valve so as to result in the most efficient and reliable operation of the apparatus.

Other objects and advantages of my invention, in addition to compactness of assembly, economy in manufacture and instal-

lation, and reliability of operation, should be readily appreciated as the invention becomes better understood by reference to the following description, when considered in connection with the accompanying drawings.

Referring to the drawings:

Fig. 1 is a side elevation, partially in vertical section, illustrating a means for carrying my improved method into effect;

Fig. 2 is a sectional view on the line 2—2 of Fig. 1;

Fig. 3 is a sectional view on the line 3—3 of Fig. 2;

Fig. 4 is a sectional view on the line 4—4 of Fig. 1;

Fig. 5 is a diagrammatic view of the control circuit for closing the valve;

Fig. 6 is a chart illustrating the position of the various switches during an operation cycle; and

Fig. 7 illustrates diagrammatically the introduction of the resistance in the motor circuit.

Referring to the drawings more in detail, and particularly to Figs. 1 to 4, inclusive, thereof, reference character 8 indicates the casing of a gate valve equipped with a valve seat 9. Upon the bonnet 11 of the valve casing is mounted a standard or yoke 12, through which the valve stem 13, carrying at its lower end the valve 14, extends. The upper portion of the valve stem is threaded and engaged by a rotatable sleeve nut 15, provided at one side with a radially projecting lug 16. The hub 17 of a gear 18 rotatably surrounds the nut 15, and is provided upon its interior with an inwardly projecting lug 19 adapted upon rotation of the gear to engage with the lug 16 and thereby rotate the nut 15. The hub 17 is journaled at its upper and lower ends upon the sleeve nut 15, as shown in Fig. 1, and a lock nut 21, threaded onto the upper end of the sleeve nut 15, prevents displacement of the hub. A hand wheel 22 surrounds the hub 17 and is secured thereto by pins 23. The gear 18 meshes with and is driven by a pinion 24, mounted upon the upper end of a shaft 25, which carries a gear 26 at its lower end, in turn meshing with and driven by a pinion 27, fixed upon the shaft of a motor 28, which is mounted upon the standard 12.

Assuming that the parts are in the position shown in Figs. 1 and 4, with the valve closed against its seat, if the motor is now started, the gear 18 and its hub 17 will be rotated in a counter-clockwise direction, viewing Fig. 4. Since during practically a complete revolution of the hub 17, substantially no resistance is offered to its movement, the motor during this period will be permitted to speed up and attain considerable momentum, which, when the lug 19 finally engages the lug 16, is applied as a hammer blow against the nut 15 to break

the valve 14 away from its seat. It will be obvious that this construction greatly facilitates the initial opening movement of the valve, and without imposing excessive strains upon the motor, which would inevitably result if the initial movement of the valve away from its seat were produced by a steady torque exerted through a continuous connection which did not include the lost motion connection provided between the sleeve 15 and the hub 17.

Upon the standard 12 there is also mounted a limit switch housing 29, within which is disposed a limit switch comprising a threaded rod 31, engaged by a nut 32 which travels longitudinally of the rod when the rod is rotated. The upper end of the rod projects above the housing 29, and has mounted thereon a gear wheel 33, which meshes with and is driven by a gear 34 secured by a key 35 to the sleeve nut 15. Rotary movements of this sleeve nut are therefore transmitted to the threaded rod 31 to cause movement of the nut 32 longitudinally of the rod. A stationary guide rod 36 extends through the nut 32 to prevent rotation of the nut.

The nut 32 carries a pair of adjustable abutment screws 37 and 38, projecting downwardly and upwardly, respectively, from the nut. Near the lower end of and within the housing 29 there is mounted a contact switch, designated generally by reference character A. The switch comprises a stationary contact piece 39 and a movable contact member 41, carried upon a bell crank lever fulcrumed at 42 upon an insulated block 43. An abutment 44, mounted upon one arm of the bell crank member, is disposed in the path of travel of the abutment screw 37, and this abutment is connected by a wire 45 with a binding post 46 connected to the circuit wire 47; as will be later explained. The contact member 39 is connected with the circuit wire 48.

Within the upper portion of the housing 29 there is mounted a similar contact switch B, the structural details of which are generally similar to the switch A, just described, and it is therefore not believed to be necessary to describe the same minutely.

It will be apparent, therefore, that upon closing movement of the valve 14, the limit switch nut 32 will travel downwardly upon the rod 31, until, through the abutment screw 37, the contact switch A is opened; and that upon opening movement of the valve, the nut 32 will travel upwardly upon the rod 31 until, through the abutment screw 38, the contact switch B is opened.

The control of the motor, by which the method of closing the valve, previously explained, is carried out, will be best understood by reference to the diagrammatic disclosure of Fig. 5. Referring to this figure,

51 and 52 indicate the power lead-in wires, from which current is fed to the motor 28 and the control circuit, through a manually operable main switch 53. It should be understood that the electrical equipment is illustrated diagrammatically only, and that standard or other preferred apparatus may be employed in the circuit to accomplish the desired results. It should further be understood that the circuit is illustrative merely, the one shown in Fig. 5 being adapted for a D. C. reversible motor; whereas, if an A. C. motor be employed, a different hook-up would be required, although the principles of operation and the results secured would be the same as are obtained with the D. C. hook-up shown herein merely as illustrating the principles of my invention.

20 Assuming that the valve is in fully opened position, that the switch 53 is open, and that the circuit is dead, the first operation in closing the valve is to close the switch 53, which is done manually. Current will now flow through the wires 54 and 55 through the solenoid 56, the contact switch C, and the wire 57, establishing a circuit which energizes the solenoid 56 to close the normally open contact switches D and E. 25 At the same time a circuit is closed through wires 54, 55, 58, the solenoid 59, wire 61, solenoid 62, wire 47, switch A, wire 48, and wire 63 to energize solenoid 59, thereby closing contact switch F, and opening contact switch G, and at the same time energizing solenoid 62, to open the normally closed contact switch H. As soon as contact switches D, E are closed, current will be fed directly to the motor 28 through the circuit, including the wires 64, 65, the switch F, and wire 66, as illustrated in the upper diagram mark "Close" in Fig. 7. The motor will therefore operate at full speed and torque to move the valve toward closed position. The nut 32 of the limit switch will simultaneously travel downwardly upon the revolving threaded rod 31, and when the valve has reached a predetermined position in proximity to its seat, determined by the adjustment of the abutment screw 37, this screw will engage the abutment 44 of the switch A, thereby swinging the movable member of the switch on its fulcrum 42 to open the switch and break the circuit in which it is included.

60 The breaking of this circuit de-energizes the solenoid 59, thereby permitting the switch member controlled thereby to resume the normal position shown in Fig. 5, opening the circuit through the switch F and closing the circuit through the switch G. This action imposes resistance 67 in series with the motor, and resistance 68 in parallel with the motor through the switch G, as shown in Fig. 5, and as illustrated diagram-

atically in the second position shown in Fig. 7, and indicated "Limit." The imposition of these series and parallel resistances in the motor circuit reduces both the speed and torque of the motor, which continues to operate, however, to force the valve against its seat. Since the final closing movement of the valve is effected under reduced speed and torque of the motor, the valve will not be jammed so violently 70 against its seat as to cause injury to the operating mechanism. When the valve becomes fully seated so that further movement thereof is precluded, the motor will stall, but because current is being supplied thereto only in materially reduced quantities, there is no liability of the motor coils becoming burned out or even unduly overheated when the motor becomes stalled.

75 The breaking of the circuit in which the switch A is included also de-energizes the solenoid 62, which thereupon releases the movable member of the switch H, permitting this switch to resume its normal closed position, as shown in Fig. 5. The closing of this switch sets in operation a time relay 69, included in the circuit with the switch H, which relay, after a predetermined period of time for which it is designed has elapsed, will actuate the movable member of the 80 switch C to open this switch. Since the time relay 69 is a commercial article, of which any one of several types may be employed, the details thereof are not illustrated herein, it being sufficient for an understanding of 85 the present invention to comprehend that a delayed action is involved so that when a circuit is established through the relay, some little time, in the present instance a few seconds, elapses before the switch C is opened 90 by the relay. In the present instance the relay is so designed that the switch C will not be opened until after the valve has been fully closed and the operating motor has become stalled. The opening of the switch C 95 de-energizes the solenoid 56, thereby permitting the movable members of the switches D and E to resume their normal open position, so as to shut off the current to the motor. The switch 53 may then either be 100 manually opened, or preferably is automatically opened by the opening of the switches D and E.

105 The position of the various contact switches during the cycle is illustrated diagrammatically in Fig. 6, from which it will be observed that when the closing movement of the valve is started by throwing in the main line switch 53, contacts A, C, D, E, and F are either already or become immediately closed in the manner previously described, while contact B remains open under the influence of the abutment screw 38, and contacts G and H become immediately 110 opened through energizing of the solenoids 115 120 125 130

59 and 62, as previously described. Upon closing movement of the valve, contact B closes as soon as screw 38 is withdrawn therefrom. When the valve reaches a point 5 in proximity to its seat, at which point screw 37 opens switch A, thereby de-energizing solenoids 59 and 62, switch F opens, and switches G and H close. When the time 10 relay 69 operates, all of the switches, with the exception of B, G, and H, which are normally closed, open and the circuit remains dead until the main switch 53 is again closed.

I have shown herein the closing circuit 15 only, but it should be understood that the wire 71, connected with the stationary member of the switch B, is included in another circuit similar in all material respects to that just described, but which reverses the current supply to the motor when a switch similar to 53 is closed, with the result that the motor is operated in the reverse direction to open the valve and move the limit switch nut 32 upwardly until abutment screw 38 20 opens switch B, whereupon resistance is thrown into the motor circuit, as previously described, and the time relay is set in operation to shut off the current after the valve has opened and the motor is stalled. It 25 should be remembered also that when the apparatus is started for the purpose of opening the valve, the motor speeds up and attains considerable momentum before stud 19 engages stud 16 to unseat the valve with a 30 hammer blow, and obviously, when the motor is reversed to close the valve, a similar hammer blow in a reverse direction is imparted to start the valve on its downward travel.

40 It is believed that my improved method, and a preferred means for carrying the same into effect, will be understood and its advantages appreciated from the foregoing without further description, and it should be 45 manifest that the structural details illustrated and described may be varied within wide limits without exceeding the scope of the invention, as defined in the following claims.

50 I claim:

1. The method of operating a valve which comprises moving the valve under full power into proximity to its seat, closing the valve against its seat under reduced power, and thereafter automatically relieving the 55 closed valve from the closing power.

2. The method of operating a valve which 60 consists in applying maximum closing power to the valve until a point in proximity to the valve seat is reached by the valve, reducing the closing power during the remainder of the closing movement, and terminating the application of power to the valve after the same has been completely seated.

3. The method of operating a valve which 70 consists in exerting a maximum moving effort upon the valve during the major portion of its travel, exerting a lesser moving effort thereon during the remainder of its travel and for a limited time after such movement has been arrested, and thereafter automatically causing the cessation of said effort.

4. The method of operating a valve which 75 consists in imposing a previously acquired momentum on the valve to start the same in motion, continuing the motion of the valve under a predetermined motive effort to a predetermined point in its travel, applying a reduced motive effort to effect the final closing movement of the valve, and automatically causing the cessation of said motive effort after the motion of the valve has ceased.

5. The combination with a valve, of means 80 including a motor and a control therefor, for moving said valve under full power toward its seat to a predetermined point, then completing the closing movement of the valve under reduced power, and finally automatically shutting off the power after the valve is seated.

6. The combination with a valve, of a 85 motor connected thereto to operate the same, means for reducing the effective torque of said motor when the valve reaches a predetermined point in its travel, and means for automatically shutting off the application of power to the motor at the expiration of a predetermined time after said predetermined point has been reached by said valve.

7. The combination with a valve, of a 90 motor, driving means including a lost motion connection between said motor and said valve, and a control for said motor including a limit switch for imposing resistance in the motor circuit and a time relay for shutting off the motor a predetermined time 95 after said limit switch operates.

8. The combination with a valve, of a 100 motor, an operative connection between said motor and said valve, and a control for said valve including means for introducing parallel and series resistance into the motor circuit at a predetermined point in the travel 105 of the valve and a time relay rendered operable by said last mentioned means for shutting off the current to said motor after the valve has become fully seated and the motor is stalled.

9. The combination with a valve, of an 110 operating motor therefor, and control means 115 for said motor for reducing the speed and torque of the motor as the valve approaches its seat and for shutting off the power to the motor after the valve has been fully seated.

CLINTON H. BECKWITH.
